UNITED STATES PATENT OFFICE.

ADOLPH KASSLER, OF NEW YORK, N. Y., ASSIGNOR TO AMERICAN CAR AND FOUNDRY COMPANY, OF NEW YORK, N. Y., A CORPORATION OF NEW JERSEY.

HOPPER CAR.

Application filed August 16, 1923. Serial No. 657,721.

Reference is had to the accompanying drawings, which illustrate the preferred form of the invention, though it is to be understood that the invention is not limited to the exact 5 details of construction shown and described, as it is obvious that various modifications thereof within the scope of the claims will occur to persons skilled in the art.

In said drawings:

10 Fig. 1 is a plan view of a car built in accordance with the invention, portions of the hopper and the doors being torn away to more clearly show the door operating mechanism;

15 Fig. 2 is partly a side elevation and partly a sectional view taken on line 2—2 of Fig. 1 looking in the direction indicated by the arrows, and showing portions of the car and door broken away to show the transmission mechanism and one method of connecting said transmission to the door supporting brackets;

20 Fig. 3 is a vertical sectional view taken on line 3—3 of Fig. 1 looking in the direction indicated by the arrows showing a view of the mechanism mounted at the end of one of the doors and a section through the other of the doors showing the transmission mounted for movement therewith;

25 Fig. 4 is a vertical sectional view taken transversely of the car showing one end of the door mechanism operating shaft and the worm and gear housing;

30 Fig. 5 is an enlarged vertical sectional view taken on line 5—5 of Fig. 4 looking in the direction indicated by the arrows showing the worm and gear and a longitudinal transmission shaft assembled within the housing;

35 Figs. 6 to 11, inc., show the relation between the longitudinal transmission shafts at opposite sides of the car and their respective gears at different stages of door operation;

40 Fig. 12 shows a modified form of the door supporting bracket illustrated in Fig. 3 using an equalizing lever for connecting the doors;

45 Fig. 13 is a vertical sectional view through one end of the equalizing lever and a door supporting arm; and

50 Fig. 14 is a plan view of said modified assembly.

My invention relates to door raising and supporting and releasing mechanism for hopper cars having a single discharge opening closed by a pair of doors hinged to the car sides, and has for one of its objects the pro-

vision of power transmission mechanism positioned out of the path of the discharging lading.

Another and important object is to utilize part of the transmission mechanism for pivotally supporting the doors at the sides of the car, other parts of said transmission being mounted upon and movable with said doors.

A further object is to so apply the door actuating power to the transmission mechanism moving with the doors that the door lifting levers at the ends thereof will be operated simultaneously.

In said drawings, 10 represents a hopper car body assembled with a supporting underframe comprising side sills 11 made up of outer and inner longitudinal members 12 and 13, respectively, connected by spacing diaphragms 14 and cover plates 15. Each cover plate 15 extends inwardly from its respective side sill member 13 and is bent downwardly at 16 to provide a seat and attaching flange for the hopper side sheet 17 sloping upwardly and outwardly to the side wall plate 18 to the lower margin of which the hopper sheet 19 is secured as best shown in Fig. 3. Resting upon the side sill and underlying the hopper side sheet 17 are the triangular bracing gussets 19 for transmitting the load on the hopper sheet directly to the underframe. Upright connection strips 20 at the car side and the inside stakes 21 are provided to further tie and brace the structure to withstand the severe service of the ore carrying roads for which service the invention is primarily designed.

Connected to the side wall and hopper side sheets are the sloping end floors 22 at each end of the hopper opening 23 and arranged in any approved manner. The sloping end floor 24 shown in the drawings comprises a central flanged section 24 and side sections 25 secured thereto, the assembled sections being secured to and supported upon a door supporting bracket 26 connecting a pair of draft sills 27 extending from the sloping end floor to the car end and connected with adjacent bolster 28. Secured to the sloping end floor and side sills are baffle plates 29 designed to guide the contents of the car into the pockets 30 of the ore docks and to prevent the lading from accumulating on portions of the dock between the pockets, serving also to keep the

wheels and journal boxes free of the discharging material.

The discharge opening 23 is unobstructed by any part of the car framing or door operating mechanism and extends between the hopper side sheets 17 and sloping end floors 22. The opening is closed and the lading supported by a pair of longitudinal doors 30, their free edges meeting at the center of the 10 car and pivotally supported at their opposite edges upon brackets 31 secured to the side sills under the inwardly projecting cover plates 15 and the hopper side sheets 17 away from the discharge opening. The 15 doors are stiffened by laterally extending braces 32 secured to the underside of said doors and spaced apart longitudinally of the doors. These braces 32, or members 33 secured to them, may form the supporting 20 hinges for the doors. The braces 32 are connected at the free edges of the doors by longitudinal members 34 extending for a least the length of the doors and adapted to transfer the load upon the doors to the door supporting brackets 26 on the underframe. To 25 prevent the lading from entering the space under the hopper side sheets 17, the adjacent edges of the doors with their braces 32 are made to extend past the downwardly projecting flange 16 as shown in Fig. 3.

The transmission mechanism comprises a longitudinally arranged shaft 40 journaled in the brackets 31 on the side sill. Upon this shaft the door hinges are loosely mounted 35 between the jaws 33 of the brackets 31 and the doors swung therefrom. This shaft extends from one end of the door to the bolster 28 beyond the opposite end of said door. A housing 41 on said bolster receives the adjacent end of shaft 40 upon which is loosely mounted for relatively limited rotation a gear wheel 39 held from movement longitudinally of the shaft by the housing walls 43 in which the end of the shaft 40 is journaled as best shown in Fig. 5. Secured to the 45 shaft portion within the hub 38 of the gear wheel 39 is a driving lug 44 adapted to engage the opposite faces of a lug 37 forming part of the bore of the gear wheel 39, the lug 37 being formed by coring out the wheel hub interior as shown at 36, Figs. 5 to 11, inc., the lug 44 moving within the cored out portion between the opposite faces of lug 37 for a purpose hereinafter to be described.

55 At the free edge of the door and movable therewith is mounted a second transmission shaft 45 journaled in bearings 46 positioned at intervals along the door and secured to the stiffening longitudinal member 34 and preferably also to the lateral braces 32. Operatively connecting the shafts 40 and 45 about midway the length of the door is a counter-shaft 47. The shafts are connected by gear spiders 48 supporting the counter-shaft 47 and loosely mounted on the parallel

shafts 40 and 45. The spiders 48 are each made up of a pair of similar sections 49 comprising a sleeved portion 50 for receiving either of the longitudinal shafts 40 or 45 and a counter-shaft bearing portion 51 at an 70 angle to the sleeved portion 50. The counter-shaft bearing portion 51 of each section is a half-bearing so that when the sections are assembled with the counter-shaft, the half-bearing of each will complement the other 75 to form a complete bearing portion 51 for the counter-shaft. The sections are held together and to the counter-shaft by means of the interengaging lugs 52, the lug on one section entering an opening in its companion 80 section, the lugs being threaded for securing nuts 53. It may be desirable in some cases to substitute separate fastening bolts for the lugs 52 but the integral lugs are preferred.

The counter-shaft 47 is provided at its ends 85 with relatively fixed bevel gears 54 in position to mesh with similar gears 55 and 56 mounted respectively on shafts 40 and 45 and fixed for rotation therewith. The gears 54 respectively engage the inner sides of the 90 gears 55 and 56 so that the shafts 40 and 45 will have relatively opposite rotation as will be evident. Fixed to the ends of shaft 45 are the door lifting crank arms 57 spaced apart to receive door supporting links 58 95 pivotedly secured by pins 59 to their respective door supporting brackets 26 and by pins 60 to the crank arms. The supporting links 58 are bowed as illustrated to straddle the shaft to permit the shaft to lie to one side of 100 a line passing through the center of pivot pins 59 and 60 to lock said shaft against rotation.

Adjacent one end of the doors is a transversely extending operating shaft 61 operable from either side of the car. The shaft is provided with worm gears 62 reversely pitched and arranged to mesh with gears 39 on the door supporting shafts 40. The worms are protected by a removable housing portion 110 63 secured to housing 41 by bolts 64, the housings combining to provide means insuring meshing engagement of the gears. The operating shaft is journaled at its ends in brackets 65 in which is also journaled a pawl 115 shaft 66 carrying a pawl 67 for engagement with a ratchet wheel 68 on the operating shaft 61. To provide means for throwing the pawl 67 into and out of locking engagement with the ratchet wheel 68 the pawl shaft is provided with operating handles 69 which serve also as counterweights to hold the pawl in locked or released position.

The operating conditions in the ore fields are severe, the ore frequently adhering to the doors in such volume as to prevent the doors from reaching their full closed position. In the case of doors operated simultaneously as here presented, any interruption in the raising movement of one door will stop the com- 120 125 130

panion door. To meet this difficulty and to insure further movement of at least one of the doors, there may be provided an equalizer bar 70 to the ends of which the door supporting links 58 may be pivotally secured. The equalizer bar is pivotally supported by pin 71 on the door supporting bracket 26^a as best shown in Figs. 12 and 13. Upon failure of one door to reach full closed position, the bar 70 will be caused to rock on its fulcrum 71, the end of the bar 70 at the lagging door side will move downwardly while the opposite end of said bar will move upwardly carrying with it the opposite door through the medium of the respective crank arms 57 and door supporting links 58. In this embodiment of the invention the door supporting links 58 are provided at their upper ends with jaws 58^a straddling the ends of the bar 70 as shown in Figs. 12, 13 and 14.

In operation, assuming the doors to be in their locked raised position, the doors are released by first rotating the pawl shaft 63 to disengage the pawl 67 from the ratchet wheel 68. The operating shaft 61 is then rotated by means of a handle bar (not shown) applied to one of the square ends of the shaft. The reversely pitched worms 62 meshing with their respective gears 39 will cause the gears to rotate in the direction indicated by the arrows in Figs. 6 and 7. During this period of movement the gears 39 turn idly upon the shafts 40 until the lugs 37 on the gears reach a position abutting shaft lug 44 as shown in Figs. 6 and 7, whereupon a further movement of the gears will cause rotation of shafts 40 and effect simultaneous rotation of counter-shafts 47 and transmission crank shafts 45 through the medium of the bevel gear connections above described, transmitting the power of the operating shaft ultimately to the crank arms 57.

The rotation of transmission crank shafts 45 will move the crank arms 57 until the line passing through crank pins 60 and door supporting link pins 59 shifts to the opposite side of the dead-center position of the crank shaft 45 causing the crank arms and links to progressively assume the several positions during the movement of the doors to their dropped open position, all as indicated in broken lines in Figs. 3 and 12. In the locked positions of cranks and links they lie substantially at right angles to the underside of the door with crank shaft center between the line coinciding with the centers of crank pins 60 and link pins 59 and the links thereby directly supporting the doors and relieving all the shafts of all torsional stresses when the doors are in their closed position. As the doors move to their open position under the weight of the load, the transmission shafts will rotate in the relatively opposite directions indicated by the arrows in Figs. 8 and 9, causing their respective lugs 44 to race away from the lugs

37 on the gears 39 which, with the operating shaft 61, remain relatively stationary during such movement of the transmission mechanism and doors. Such movement of doors and transmission mechanism independently of the operating shaft will prevent injury to the operator resulting from the wresting of the operating handle from his grasp upon starting of the mechanism since such movement is not communicated to the operating shaft. A reverse rotation of the operating shaft will cause the simultaneous movement of transmission shafts and their respective gears from the position shown in Figs. 8 and 9 to the initial locked position of said parts as shown in Figs. 10 and 11, the gears rotating in the direction indicated by the arrows in said last mentioned figures. This operation raises the doors and restores the crank arms and links to their locked position as best shown in full lines in Figs. 3 and 12. The pawl shaft is then rotated to throw the locking pawl into engagement with the ratchet wheel.

Due to the relatively low side of the car and the position of the locking mechanism it is difficult at times to determine whether or not the doors have reached their locked positions. To provide a simple means for indicating the locked position of the doors there is provided on opposite sides of the car a device in the nature of a semaphore comprising a bar 75 preferably sleeved on shaft 40 and fixed to rotate therewith by set-screw 76. This bar is so adjusted initially that it will lie against the side sills 11 when the doors have reached their locked position, all as indicated in Figs. 3 and 12. When the doors are unlocked the semaphore will stand away from the side sill and will not be visible, which fact will convey to the operator the information that the doors are not raised or, if raised, are not locked.

From the foregoing it will be noted that each door of the pair used is provided with its own transmission mechanism, being connected to the transmission of the other door for simultaneous operation through the medium only of the operating shaft 61; that the transmission mechanism of each door is for the greater part positioned within the area of the door and away from the door opening; and that the power is applied to the transmission crank shaft 45 midway its length thereby minimizing the torsional stresses in the shaft between the point of application of power, the counter-shaft position, and the crank arms.

What I claim is:

1. A hopper car having a single discharge opening and a pair of longitudinally arranged drop doors hinged at the car sides and closing said opening, transmission mechanism carried by said doors, an operating shaft adjacent one end of said doors and con-

necting the transmission mechanism of one door to the other, and loose connections between said operating shaft and transmission mechanism.

5 2. In a dump car having a plurality of drop doors, door lifting mechanism carried by said doors and including a crank shaft, and counter-shaft mechanism connected with said crank shaft and movable with said doors.

10 3. In a door operating mechanism for cars having a single unobstructed discharge opening and a pair of drop doors closing said opening, separate door raising mechanisms having portions movable with said doors,

15 each of said mechanisms including a crank shaft, and counter-shaft mechanism connected to said crank shaft, portions of said door raising mechanism being adapted to pivotally support said doors and counter-shaft.

20 4. In a hopper car comprising a single discharge opening, sloping end floors and hopper side sheets defining said opening, a pair of drop doors pivoted longitudinally of said opening, a supporting underframe, and door lifting mechanism comprising shafts movable with said doors and operating shafts supported on said underframe and having said doors pivotally mounted thereon.

25 5. A door operating mechanism for cars having a single unobstructed discharge opening and a plurality of drop doors closing said opening comprising power transmissions having portions movably mounted on said doors, operating shafts of said transmission mechanism being adapted to pivotally support said doors.

30 6. The combination with the drop doors of a dump car having a single discharge opening, of door actuating mechanism having portions supported by and movable with said doors, operating shafts of said actuating mechanism pivotally supporting said doors.

35 7. In a hopper car having a single discharge opening and a supporting underframe, power transmission mechanism having operating shafts supported on said underframe adjacent said opening, and a pair of drop doors closing said opening and mounted upon said shafts, other portions of said mechanism being mounted upon and movable with said doors.

40 8. In a hopper car having hopper side and sloping end floor sheets defining a single discharge opening, a supporting underframe, a pair of longitudinally arranged doors closing said opening, door supporting brackets connecting the sloping end floor sheets and underframe, and door lifting mechanism moving with said doors and having pivotal connection with said brackets.

45 9. In a hopper car having hopper side and sloping end floor sheets defining a single discharge opening, a supporting underframe, a pair of longitudinally arranged doors closing said opening, door supporting brackets

connecting the sloping end floor sheets and underframe, and door lifting mechanism supported on said underframe and movable with said doors, said mechanism having pivotal connection with said brackets.

50 10. In a hopper car having a single discharge opening, a supporting underframe, a pair of longitudinally arranged doors closing said opening, door supporting brackets connecting said hopper and underframe, separate door actuating mechanism for each door comprising a door supporting shaft, a parallel crank shaft journaled on the door at the free edge thereof, a counter-shaft supported upon and operatively connecting said shafts, crank arms at the ends of said crank shafts, door supporting links connecting said crank arms and door supporting brackets, and a common operating shaft connecting the door supporting shafts.

55 11. In a car provided with a hopper having a single discharge opening, a supporting underframe, a pair of longitudinal drop doors hinged at the car side for closing said opening, door lifting mechanism supported on said underframe and movable with said doors, door supporting brackets connecting said underframe and hopper, equalizing bars pivotally mounted on said brackets, and crank arms and supporting links pivotally connecting said equalizing bars to the door lifting mechanism.

60 12. A hopper car having a single discharge opening and a pair of longitudinally arranged drop doors hinged at the car sides and closing said opening, door lifting mechanism including a shaft for pivotally supporting said doors, and a semaphore bar fixed for rotation with said shaft and adjusted to a predetermined position with respect to the car when the doors are in their locked raised position.

65 13. In a door operating mechanism for cars having a pair of longitudinally arranged drop doors, door raising mechanism comprising a door supporting shaft and a parallel crank shaft, a counter-shaft between said door supporting and crank shafts, and gear spider elements connecting said shafts.

70 14. In a car having a single discharge opening and a plurality of drop-doors closing said opening, a door-operating mechanism comprising door-operating shafts pivotally connecting said doors to the car body, said doors being freely movable upon said shafts.

75 15. In a car having a discharge opening, a door-operating shaft rotatably mounted adjacent said opening and a door for said opening freely mounted on said shaft.

80 16. In a car having a discharge opening, a door-operating shaft rotatably mounted adjacent said opening, a door for said opening freely mounted on said shaft and means mounted on said door operatively connecting said shaft and door.

85 17. In a hopper car having hopper side

130

- and sloping end floor sheets defining a single discharge opening, a supporting underframe, a pair of longitudinally arranged doors closing said opening, door-supporting brackets, 5 connecting the sloping end floor sheets and underframe, door lifting mechanism comprising shafts moving with said doors and crank arms carried by said shafts and means connecting said crank arms and door-supporting 10 brackets.
18. In a car provided with a hopper having a discharge opening, a supporting underframe, drop-doors for closing said opening, door-supporting brackets connecting said 15 underframe and hopper, shafts carried by said doors, crank arms carried by said shafts and means connecting said crank arms and door-supporting brackets.
19. In a car provided with a hopper having 20 a discharge opening, a supporting underframe, drop-doors for closing said opening, door-supporting brackets connecting said underframe and hopper, shafts carried by said doors, crank arms carried by said shafts, 25 means connecting said crank arms and door- supporting brackets and operating shafts for said crank shafts pivotally connecting said doors and underframe.
20. In a dump car, drop doors, door operating mechanism comprising crank and counter shafts carried by said doors and operating shafts for said counter shafts pivotally supporting said doors. 30
21. In a dump car, an underframe, drop doors, door operating mechanism comprising crank shafts carried by said doors, cranks carried by said crank shafts, means connecting said cranks to said underframe and means for operating said crank shafts pivotally supporting said doors. 35
22. In a dump car, a door operating shaft, a door operated by said shaft and pivotally mounted thereon and a semaphore bar carried by said shaft. 40
23. In a dump car, a door operating shaft and a door operated thereby and rotatably mounted thereon. 45

In witness whereof I have hereunto set my hand.

ADOLPH KASSLER.
